UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI, A CORPORATION.

DOOR OPENING AND CLOSING DEVICE.

No. 852,814.

Specification of Letters Patent.

Patented May 7, 1907.

Application filed October 11, 1906. Serial No. 338,391.

To all whom it may concern:

Be it known that I, HUBERT WITTE, a citizen of the United States of America, residing in the city of St. Louis, in the State of Missouri, have invented certain new and useful Improvements in Door Opening and Closing Devices, of which the following is a full, clear, and exact description, reference being had to the accompanying drawings, forming part of this specification.

My invention relates to a device for opening and closing doors and more particularly doors used upon the platforms of railway cars, the object of the invention being to provide a door opening and closing mechanism that may be operated by one of the crew of a car, for instance the conductor or motorman to permit the entrance or exit of passengers into or from the car across a platform thereof.

Figure I is a view partly in horizontal section through one end of a railway car and partly in top or plan view and illustrating my door operating mechanism in the position assumed when the door operated thereby is in closed position. Fig. II is a similar view to Fig. I, showing the door operating mechanism in the position assumed when the door is in opened position. Fig. III is in part a vertical section taken through the end of the car and in part an elevation of the door operating mechanism and the door in closed position. Fig. IV is an enlarged vertical section taken on line IV—IV, Fig. III.

1 designates the platform of a railway car which is surmounted by a front wall containing posts B and C. The space above the platform A is subdivided to provide a passageway leading to the interior of the car from the steps of the platform, as indicated at D, this division being preferably effected by a partition E and the door F, the door being provided for the purpose of furnishing a wall for said passageway and also for the purpose of permitting the person who is to operate the door mechanism to pass from the passageway D of the platform to the other portion of the platform which he occupies, during the operation of the door.

2 designates a door section that is hinged at 2 to the platform post C and is adapted to swing inwardly over the platform in a direction toward the partition E.

3 is a second door section that is connected by hinges 4 to the first-named section, the

hinges being located at the outer sides of the door sections, in order that when the two door sections are moved inwardly the second door section 3 may become folded against the outer side of the first door section 1. Above the door consisting of the sections 1 and 3 is a channel shaped track rail 5.

6 is a guide arm secured to the door section 3 and to which is journaled an anti-friction roller 7 that is adapted to travel in the track rail 5 for the purpose of guiding and steady- 65 ing the door section 3 during the period of moving the sectional door from its closed to its open and folded position and vice versa.

8 designates a rock shaft that is vertically positioned in the space above the platform A 70 occupied by the person who is to operate the door operating means, this rock shaft being preferably journaled in boxes, one of which, as indicated at 9, may be attached to the platform wall post B and the other of which 75 may be mounted upon the platform as seen at 10.

11 is an operating handle fixed to the rock shaft 8. The rock shaft preferably extends beneath the platform and it has fixed to it a 80 crank arm 12.

13 is a link pivoted at one end to the crank arm 12.

14 is a vertical rock shaft located adjacent to the partition E and preferably mounted in 85 a box 15 secured to said partition and a box 16 mounted upon the platform. The rock shaft 14, like the rock shaft 8, preferably extends beneath the platform and has fixed to it a crank arm 17 that receives the connection of the connecting link 13 (see full lines Fig. III and dotted lines Figs. I and II.)

18 designates a lever arm fixed to the rock shaft 14 and extending therefrom through the partition E to the passageway D, a horizontal slot E' being provided in said partition for this purpose (see Fig. III.) The lever arm 18 is connected by a rule-joint at 19 to a connecting link 20 that is in turn pivoted at 21 to a swing arm 22 loosely connected to the door section 3 by attachment at 23 to a bracket 24 which is permanently fastened to said door section.

25 is a guide bracket mounted in a horizontal position upon the partition E at the side 105 thereof facing the passageway D and which contains a channel shaped guideway 26.

27 is a guide arm pivotally connected to

the connecting link 20 and the swing arm 22 at the point 21 and provided at its other end with an antifriction roller 28 (see dotted lines Figs. I to III inclusive) that is adapted 5 to operate in the guideway 26.

Assuming the door consisting of the sections 1 and 3 to be in closed position, as seen in Fig. I, the operator to open the door grasps the handle 11 of the rock shaft 8 and by moving 10 said handle into the position shown in Fig. II causes both the rock shaft 8 and the rock shaft 14 to be rotated in the same direction due to the connections between them, and the lever arm 18 to be moved in a direction 15 toward the rock shaft 8. As a consequence of this movement of the lever arm a pull is effected upon the connecting link 20 and the swing arm 22, the rule-joint between the lever arm and connecting link being 20 broken during this action. As a consequence the swinging arm 22 is caused to exert a pull upon the door sections 3 and 1, so that the former is folded against the latter and the two sections are moved into the folded and 25 open position illustrated in Fig. II. During this folding and opening of the door sections the section 3 is properly guided relative to the section 1 through the medium of the guide arm 6 and its anti-friction roller 7 operating in conjunction with the guide rail 5. Also during the movement of the lever arm, connecting link and swing arm the movement 30 of the connecting link and swing arm is directed by the guide arm 27 having the anti-friction roller 28 that travels in the guideway 26 of the bracket 25. In closing the door the movement of the parts is in all 35 essentials the reverse of that described in connection with the opening of the door and 40 therefore more detailed description on this point is deemed unnecessary.

I claim:

1. In a door opening and closing device, the combination with a door, of a swing-arm

connected to said door, a rock-shaft, lever 45 connection between said rock shaft and swing-arm, a guide bracket, a guide arm pivoted to said lever connection and slidably fitted to said bracket, and means for operating said rock-shaft, substantially as set forth. 50

2. In a door opening and closing device, the combination with a door, of a swing-arm connected to said door, a rock shaft, a lever fixed to said rock shaft, a connecting link pivotally connecting said lever and swing-arm, a guide arm pivoted to said connecting link and swing-arm at a point of their connection, a guide in which said guide arm operates, and means for operating said rock shaft, substantially as set forth. 55

3. In a door opening and closing device, the combination with a sectional door, of a swing-arm connected to one of the sections of said door, a rock shaft, means for operating said rock shaft, a lever fixed to said rock 65 shaft, a connecting link pivoted to said swing arm and having rule-joint connection with said lever, a guide bracket, and a guide arm having pivotal connection with said swing-arm and link and slidably fitted to 70 said guide bracket substantially as set forth.

4. In a door opening and closing device, the combination with a sectional door, of a swing-arm connected to one of the sections of said door, a rock shaft, means for operating said rock shaft, a lever fixed to said rock shaft, a connecting link pivoted to said swing-arm, a guide bracket having a guideway therein, and a guide arm pivoted to said swing-arm connecting link at the point of 80 connection thereof and arranged to operate in the guideway of said guide bracket, substantially as set forth. 75

HUBERT WITTE.

In presence of

GEO. W. FULLER,
LOUIS NIEHAUS.
